UNITED STATES PATENT OFFICE.

OREL D. ORVIS AND NELSON B. ADAMS, OF NEW YORK, N. Y.

CABLE RAILWAY.

SPECIFICATION forming part of Letters Patent No. 323,593, dated August 4, 1885.

Application filed November 18, 1884. (No model.)

To all whom it may concern:

Be it known that we, OREL D. ORVIS and NELSON B. ADAMS, both of the city and county of New York, in the State of New York, have invented a new and useful Improvement in 5 Cable Railways, of which the following is a specification.

Our invention is more particularly intended as a substitute for surface or street railways 10 in which the cars are drawn by horses, and relates to railways along which the cars are drawn or propelled by an endless cable moving in a tunnel or trough laid between the track-rails and communicating with the surface by a narrow slot or channel in which 15 moves the plate or piece which forms the connection between the moving car above the tunnel or trough and the grip mechanism in the tunnel or trough. In railways of this class the cable is supported by and travels upon supporting sheaves or pulleys in the tunnel or 20 trough. These cable-supporting sheaves have to be arranged at short distances apart—say, about fifty feet, more or less—and they have 25 commonly been supported in fixed bearings, and have had to be so arranged as to be readily accessible for the purpose of frequently oiling their bearings. Ordinarily it has been necessary to construct a deep and expensive 30 tunnel of iron and concrete, with man-holes leading from the street-surface, at short distances apart, for the purpose of gaining access to the cable-supporting sheaves or pulleys to oil them, and to inspect or renew them 35 or their bearings, when worn, so as to be unfit for use. Not only is such a structure expensive and the man-holes and covers along the street-surface objectionable, unsightly, and dangerous, but when such a structure is to be 40 built along a street to take the place of a horse-car railway already in operation, it becomes necessary to construct a temporary side track along the line of road for the use of horse-cars while the cable-railway structure is 45 being prepared. The cost of laying such temporary track, which must be afterward torn up and the street-pavement restored to its 50 original condition, is almost as great as the original cost of laying the permanent horse-car track; and in streets which are already occupied by elevated and surface railways it is in many cases impossible to lay a temporary

horse-car track while the cable-railway structure is being substituted for the original horse-car track, and in these cases traffic by the surface roads must be entirely suspended while the cable-railway structure is being prepared. Recognizing these great difficulties in the way of substituting the cable-railway systems heretofore known for the old horse-car railways, we 55 have devised a system of cable-supporting pulleys which renders it unnecessary to have a large, deep, and expensive tunnel and man-holes and covers at short distances apart, and which enables us to substitute therefor a shallow 60 and narrow trough requiring an excavation of only about eighteen inches or two feet deep by one foot wide, and to bring all the supporting sheaves or pulleys in succession to 65 one or more places along the line where they 70 may be inspected, oiled, and renewed, if desired.

In railway structures of this class as heretofore constructed it has been exceedingly difficult to maintain the longitudinal slot whereby the tunnel or trough communicates with the street-surface at the uniform and desired width; and as both this slot and the plates which move 75 therein are very narrow or thin, the slot being only about one-half of an inch wide, the plates 80 have been apt to bind or stick in the slot and entail great difficulty and delay and frequent breakages in operating cars. Recognizing this difficulty, we have combined with the above-described tunnel or trough a novel system of 85 struts or braces and tie-rods, whereby the two irons which form the sides of the slot are held forcibly apart by the weight upon the rails and are prevented from coming together or toward 90 each other as the center of the street between the rails settles.

For new roads and lines of travel our invention has great advantages, because of the cheapness of construction, the dispensing with man-holes and covers in the street, and the rigidity 95 with which the parts are held in proper position and the longitudinal slot maintained straight and of uniform width.

As a substitute for horse-car roads already laid and in operation, the invention has the great additional advantage that it provides for laying the tunnel or trough in sections, using the original rails, stringers, and cross-ties, (the latter only being cut in two,) and permits of 100.

the road being reconstructed and completed, ready for operation by cable, without discontinuing the running of cars by horses and without laying any temporary side tracks.

- 5 Our invention consists in the combination, with a tunnel or trough, and cable arranged to work therein, of a chain or system of cable-supporting pulleys or sheaves and trucks separate from and supporting the cable, and capable of movement in the tunnel or trough independently of the cable. The chain or system of sheaves or pulleys may consist of a suitable number of little trucks or frames, in each of which is journaled a cable-supporting sheave, 10 or two cable-supporting sheaves if a double cable is employed, and each of which is supported on wheels or rollers. The trucks are connected at suitable distances apart by chains, ropes, or other flexible connections, the whole 15 forming a chain or system which may be moved independently of the cable to bring the sheaves or pulleys successively to a position where they may be oiled or inspected. The chain or system of supporting sheaves or pulleys may be moved along as the cable moves and at a slower or equal speed; or the said chain or system may remain motionless when the cable is in use, and be moved for the purpose above described only when the cable is at rest.
- 20 30 The invention also consists in the combination, with the track-rails and a tunnel or trough for a cable between them, of struts or braces supporting the rails at their outer ends and extending inward and downward to the 25 tunnel or trough, and tie-rods or bolts extending from the irons which form the slot at the upper part of the tunnel or trough to the outer ends of said struts or braces, and provided with 35 screw-threads and nuts capable of adjustment 40 to put tension on the tie-rods to draw or strain apart the irons forming the slot.

The invention also consists in various other novel combinations of parts hereinafter described, and pointed out in the claims.

- 45 In the accompanying drawings, Figure 1 represents a longitudinal vertical section of portions of a railway structure embodying our invention. Fig. 2 is a longitudinal horizontal section thereof, supporting-sheaves being 50 provided for a single cable only. Fig. 3 represents a transverse section, upon a larger scale, of a railway structure illustrating our invention as applied to a new structure, a single cable only being represented. Fig. 4 is a horizontal section similar to Fig. 2, but representing 55 supporting-sheaves for two cables. Fig. 5 is a transverse section on the same scale as Fig. 3, illustrating our invention as applied to a horse-railway structure already constructed, and representing only one cable and its 60 supporting-sheaves. Fig. 6 is a section similar to Fig. 5, representing two cables and their supporting-sheaves; and Fig. 7 is a view similar to Fig. 6, showing a modification of our 65 invention.

Similar letters of reference designate corresponding parts in all the figures.

Referring first to Figs. 1, 2, and 3, A A, Fig. 3, designate the two track-rails, which are of considerable depth and have at their bottoms base-flanges *a*, whereby they are supported. Between the two rails we excavate a trench, which need only be about one and one-half or two feet deep by one foot wide, and therein we lay a small tunnel or trough 70 which communicates with the street-surface only by a narrow longitudinal slot, *b*. This tunnel or trough may be of any suitable construction; but as here shown it consists of a base-plate or sole-plate, *B*, side plates or 75 80 pieces, *B' B'*, having at their bottom edges flanges *c*, through which rivets or bolts *c** are inserted for securing them to the plate *B*, and bars or beams *B²* of rolled iron, which are riveted or bolted to the pieces *B'* and have at 85 their upper edges inwardly-projecting flanges *b'*, forming between them the slot *b*.

The several parts composing the tunnel or trough may be made in sections of suitable length and bolted or riveted together, so as to 90 break joints one with another, and in this way a continuous structure of great stiffness will be formed. The base-flanges *a* of the rails *A* rest in seats *a'*, formed in the outer ends of struts or braces *C*, which extend from said 95 rails downward and inward toward the trough or tunnel and are secured to the sides *B'* thereof. At the outer ends of said struts or braces *C*, and in this example of the invention passing directly through them, are tie-bolts 100 *D*, which extend to the irons *B²* and serve to prevent the movement of said irons *B²* inward toward each other, as well as to prevent the spreading of the ends of the struts or braces *C*, on which the rails *A* are supported.

105 By the tie-rods *D* we connect those parts which would be apt to give downward and outward under weight on the rails—*i. e.*, the outer ends of the braces or struts *C*—with those parts which would naturally tend to move inward by the settling of the street under traffic—*i. e.*, the irons *B²*—and in this way we form a strong and simple triangular support for the rails, and at the same time hold the irons *B²* against movement toward each other and 110 preserve the slot *b* straight and uniform in width. The tie-rods *D* are provided at their outer ends with screw-threads and nuts, and by screwing up the nuts the tension on the rods may be increased and the irons *B²* may 115 be drawn or strained apart to maintain the width of the slot *b*. The paving-blocks *E* fill the space between the rails *A* and the slot-irons *B²*.

F designates the cable, which will be endless, one portion thereof extending through the tunnel or trough shown, and the other and oppositely-moving portion extending through a parallel tunnel and serving for traffic in the other direction. We have also represented 125 in part the grip devices *G*, which are connected with the car by a thin plate, *G'*, moving in the slot *b*, and form no part of our present invention.

H designates the sheaves or pulleys for supporting the cable in its travel, and which should be about fifty feet apart, more or less. These sheaves are not arranged in stationary or fixed bearings, as is usual, but each sheave is journaled in a little truck or frame, I, which has wheels or rollers I' adapted to run upon the sole-plate B of the tunnel, as best shown in Figs. 2 and 3.

10 The trucks or frames I for the cable-supporting pulleys or sheaves H may be flexibly connected by wire ropes, chains, or other analogous connections, J, and they preferably form an endless chain or system of cable-supporting pulleys or sheaves which properly support the cable F in its travel, but which is capable of movement independently of the cable. The cable F may be passed around and operated by a driving-drum in the usual 20 way; and the chain or system of cable-supporting pulleys may be carried around a drum or sheave having cavities or notches in its perimeter to receive the trucks I I', and capable of being thrown into gear with the driving-engine, and operated thereby, or of being driven by an independent engine when desired. In any case the cable runs over the supporting-sheaves H as over the sheaves in fixed bearings, and is in every respect as independent of said sheaves. When the cable is in operation, the chain or system of sheaves H may be motionless as regards longitudinal travel, and when the cable is stopped this chain or system of supporting-sheaves may 30 be set in motion and moved along to bring all its sheaves in succession past a point or points where they may be lubricated, inspected, and, if necessary, repaired or renewed.

35 The chain or system of sheaves H may, if desired, be operated while the cable is in operation and at a speed slower than or equal to the speed of the cable.

40 By the arrangement and combination with the main cable of an independent chain or system of supporting sheaves or pulleys we are enabled to almost entirely dispense with man-holes and covers in the streets.

45 To keep the tunnel or trough free from dirt which must enter through the slot b, we may attach brushes d to the trucks or frames I, as is shown in Fig. 1; and as the chain or system of supporting-sheaves is moved along these brushes sweep the bottom of the tunnel or trough and move the dirt and refuse to a low 50 place or places in the tunnel or trough where there is an escape aperture or pipe, e, for dirt and for water which may drain in through the slot b. The bottom of the tunnel or the sole-plate B is left continuous in the line of 55 travel of the wheels or rollers I' to afford continuous bearing-surfaces therefor, as shown in Fig. 2. This tunnel or trough, as is usual in railway structures of this class, follows closely the grade of the street, and consequently at 60 low points in the street the cable F rises from the sheaves H, and has a tendency to crowd up into the slot b. To prevent this we ar-

range upper pulleys, f, at the low points, as shown in Fig. 1, which hold the cable out of contact with the top of the tunnel. As the 70 grip G has the cable, it raises it clear of the sheaves H, as shown by dotted lines in Fig. 1, and as the grip passes the stationary upper pulleys, f, it depresses the cable below them.

75 Fig. 4 differs from Fig. 2 only in having two cable-supporting sheaves H in each truck or frame I, thereby enabling the chain or system of supporting-sheaves to support two parallel cables, if two are used in one tunnel.

We will now describe Figs. 5 and 6, which 80 illustrate our invention as embodied in a structure which has been altered from a horse-railway, the only difference between the two figures being that Fig. 6 represents the small trucks I as each provided with two cable-supporting pulleys H, a double-grip mechanism, G, and the tunnel or trough as made correspondingly wider. In this example of our invention we employ the same rails A, stringers K, and cross-ties L which were employed 90 in the original horse-railway structure, the whole being left intact, except that we cut the cross-ties L and support the adjacent ends upon flanges or brackets g, cast or formed upon the outer sides of the pieces B'. The 95 flanges or brackets g project laterally from the outer sides of the pieces B', and their upper surfaces form flat bearings or supports on which the ends of the sections of the wood cross-tie L are properly supported. The struts 100 or braces C are here made of wood, and at their outer ends they support the rails A, through the stringers K, the ends of said struts or braces C being notched at h to fit the under side of the stringers between the cross-ties L. 105 The tie-rods D here extend through the stringers K, and through them are connected with the outer ends of the struts or braces C. The paving-blocks E are laid between the stringers and irons B' in the usual way. 110

In all the examples of our invention the sheaves H may be self-oiling, and are shown in Figs. 5 and 6 as having oil-chambers i in their hubs. This form of our invention is applicable to the reconstruction of street-railways without discontinuing the use of cars drawn by horses, the tunnel or trough being laid in sections, and the work being continued until the whole line is prepared for operation by cable. Even then the change from 115 horses to cable for propelling the cars need not be made universal and all at once, for the running of cars by horses can continue and the cars be altered gradually to adapt them 120 for operation by cable. 125

In the example of our invention shown in Fig. 7 the construction is similar to that shown in Fig. 6 in many particulars, and differs therefrom principally in not having the rolled irons B' at the top, forming the two 130 sides of the slot b, and in having the side pieces or plates, B', continued, and having formed integral with them the inwardly-projecting flanges b' which form the sides of the

slot. By this construction we are enabled to make the tunnel or trough shallower than in the previously-described examples of our invention by a difference about equal to the 5 depth of the pieces B² before described. The side pieces, B', may be made wholly of cast-iron, and the tops of the flanges b' may be roughened or serrated to give horses a firm foothold and prevent their slipping. With 10 this construction a trench eighteen inches deep will suffice. In this example of our invention, also, the stringers K, which support the rails, have braces or struts C extending from them to the tunnel, and tie-rods D, extending from them to the upper part of the 15 side pieces, B', and the same letters of reference refer to the same parts in this as in the preceding figures.

What we claim as our invention, and desire to secure by Letters Patent, is—

1. The combination, with a tunnel or trough, and a cable arranged to work therein, of a chain or system of cable-supporting sheaves or pulleys, and trucks or frames therefor 25 separate from and supporting the cable, and capable of movement in the tunnel or trough independently of the cable, substantially as and for the purpose herein described.

2. The combination, with a tunnel or trough, 30 and a cable arranged to work therein, of cable-supporting sheaves or pulleys, trucks or frames wherein they are journaled, and flexible connections between the trucks or frames, the whole forming a chain or system of cable- 35 supporting sheaves movable independently of the cable, substantially as herein described.

3. The combination, with the tunnel or trough, and cable F therein, of the sheaves H, the frames I, and their wheels I', carrying the 40 said sheaves, and flexible connections J between the frames I, the whole forming a chain

or system of cable-supporting sheaves movable independently of the cable, substantially as herein described.

4. The combination, with a tunnel or trough, 45 and a cable arranged to work therein, of a chain or system of cable-supporting pulleys or sheaves movable independently of the cable, and brushes or sweepers attached to and movable with the chain or system of pulleys 50 or sheaves, substantially as herein described.

5. The combination, with the track-rails, and a tunnel between them having at the top a slot, b, of the struts or braces C, supporting the rails at their outer ends and extending inward and downward to the tunnel, and the tie-rods D, extending from the side pieces of the tunnel adjacent to the slots and serving to confine the outer ends of the braces C, the said tie-rods being provided with screw- 60 threads and nuts, whereby tension may be applied to them to draw or strain apart the side pieces which form the slot, substantially as herein described.

6. The combination, with the track-rails A 65 A, and the tunnel between them having the slot b and the brackets g, projecting laterally from its sides, of the longitudinal stringers K, on which the rails are secured, the divided cross-ties L, supporting the stringers and having their inner ends resting and supported on the lateral brackets g, the braces C, supporting the stringers, and tie-rods D, extending from the side pieces forming the slot b to the stringers K, and provided with screw-threads 70 and nuts, whereby tension may be applied to them, substantially as herein described.
